(57) **CLAIM**

The ornamental design for a set of eyeglasses frame components, as shown and described.

DESCRIPTION

FIG. 1 is a perspective view of a set of eyeglasses frame components showing my design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof;

FIG. 7 is a bottom view thereof; and,

FIG. 8 is an enlarged perspective view thereof.

The broken line portions are not claimed. The dot dash lines depict the boundary at which unclaimed portions terminate and claimed portions begin.
